(57) **CLAIM**

The ornamental design for a spherical tape dispenser, as shown and described.

DESCRIPTION

FIG. 1 is a top view of a spherical tape dispenser showing my new design with its roll holding arm in a closed position; FIG. 2 is a bottom view thereof;

FIG. 3 is left side view thereof, with the right side view being a mirror image thereof; FIG. 4 is a front view thereof; FIG. 5 is a rear view thereof;

FIG. 6 is a front top left isometric view thereof;

FIG. 7 is a rear top right isometric view thereof;

FIG. 8 is a top view of the spherical tape dispenser of FIG. 1, but showing its roll holding arm in an opened position;

FIG. 9 is a bottom view the spherical tape dispenser of FIG. 8; FIG. 10 is a left side view of the spherical tape dispenser of FIG. 8, with the right side view being a mirror image thereof; FIG. 11 is a front view of the spherical tape dispenser of FIG. 8;

FIG. 12 is a rear view of the spherical tape dispenser of FIG. 8; FIG. 13 is a rear top right isometric view of the spherical tape dispenser of FIG. 8; and,

FIG. 14 is a front top left isometric view of the spherical tape dispenser of FIG. 8.
